UNITED STATES PATENT OFFICE.

ORRIS J. DARLING, OF DETROIT, MICHIGAN.

AIR-PUMP.

No. 886,353.

Specification of Letters Patent.

Patented May 5, 1908.

Application filed April 8, 1907. Serial No. 367,133.

To all whom it may concern:

Be it known that I, ORRIS J. DARLING, a citizen of the United States, residing at Detroit, county of Wayne, State of Michigan, have invented a certain new and useful Improvement in Air-Pumps, and declare the following to be a full, clear, and exact description of the same, such as will enable others skilled in the art to which it pertains to make and use the same, reference being had to the accompanying drawings, which form a part of this specification.

This invention relates to air pumps and its object is to provide a pump that may be used either as a force pump or as a vacuum pump. Its novelty consists in the peculiar arrangement of parts hereinafter more fully described.

In the drawing I have shown the pump as adapted for use in clearing the traps in waste pipes to sinks, etc., but the principles involved in the construction may be utilized in pumps adapted for use in other ways.

Figure 1 is a sectional elevation of a pump embodying my invention. Fig. 2 is a detail of the upper end of the hollow piston rod showing the inlet thereinto closed. Fig. 3 is a detail showing the inlet in the hollow piston rod open. Fig. 4 is a detail of the piston showing the valve in the lower end of the piston rod.

Similar letters refer to similar parts throughout the several views.

A indicates the cylinder of the pump. B is the cap on the upper end of the cylinder.

b is the vent in the cap. The lower end of the cylinder is open and in this case is provided with a rubber cup shaped foot F adapted to closely fit over the opening to the waste pipe in sinks etc. However I do not wish to limit myself to such use of the pump as it is evident that various uses could be made of it by arranging the lower or outlet end to suit the conditions.

The piston P is double acting being packed with two cup leathers p—p¹ to withstand pressure in both directions. The cup p forces air out of the cylinder on the downward stroke of the piston and the cup p¹ draws air into the cylinder on the upward stroke of the piston. The piston rod R is hollow and is provided with a valve V at or near its lower end the upper end is provided with a handle H and a cap C. The cap C is provided with

openings c—c and a packing ring or washer w so arranged that when the cap is screwed down on the end of the piston rod the openings c—c are below the end of the rod and air may not enter therethrough by reason of the packing ring w being held tightly against the end of the hollow rod R by the cap C as shown in Fig. 2. If used as a force pump, the cap C is raised, as shown in Fig. 3, so that the openings c—c are above the end of the rod. On the upward stroke of the piston P, the cylinder will fill with air which passes through the openings c into the rod R, through the valve V, and into the cylinder A. The downward stroke of the piston closes the valve V and forces the air out of the cylinder. On the upward stroke, the air that is above the piston escapes by way of the vent b in the cap B.

If the pump is used to produce a vacuum, the cap C is screwed down on the rod thus closing the openings c—c, consequently no air may get below the piston through the rod and the upward stroke thereof tends to produce a vacuum.

The valve V I have shown as a ball resting, in the open position, on a pin or bar y in the lower end of the piston rod, thus allowing the air to pass freely around it when used as a force pump and on the upward stroke. On the downward stroke, that is when forcing air out of the cylinder, the ball rests against the seat s and prevents escape of the air through the rod. Nevertheless it is to be understood that any form of valve suitable for the purpose may be used.

Having thus briefly described my invention, what I claim is—

1. In an air pump, a cylinder open at its lower end and provided with means to fit over an opening, a double acting piston, a hollow rod to said piston, a check valve in said rod, and means on the rod controlling the introduction of air thereinto, substantially as shown and described.

2. In an air pump, a cylinder provided with a cap having a vent, a double acting piston arranged to reciprocate in said cylinder, a hollow piston rod provided with a valve near the end attached to the piston, and means on the rod controlling the introduction of air thereinto, substantially as shown and described.

3. In an air pump, a cylinder, a double acting piston arranged to reciprocate in said

cylinder, a hollow piston rod provided with a valve near the end attached to the piston, and a cap on the opposite end thereof provided with a packing ring and having an opening therein below said ring whereby the inlet to said piston rod may be opened or closed, substantially as shown and described.

In testimony whereof, I sign this specification in the presence of two witnesses.

ORRIS J. DARLING.
